(Cl. D33—10)

To all whom it may concern:

Be it known that I, George A. Gallik, a citizen of the United States, residing at Duluth, in the county of St. Louis and State of Minnesota, have invented a new, original, and ornamental Design for an Altar Card Supporting Frame, of which the following is a specification, reference being had to the accompanying drawing, forming part thereof.

Fig. 1 is a front elevational view of the supporting frame showing my new design,

Fig. 2 is a side elevational view of Fig. 1,

Fig. 3 is a top plan view of Fig. 1.

I claim:

The ornamental design for an altar card supporting frame, as shown.

GEORGE A. GALLIK.
